MACHINE FOR PRESSING AND SHAPING
POINTS OF COLLAR TOPSGarry J. Dormandy, Troy, N. Y., assignor to M.
Nirenberg Sons Inc., Troy, N. Y., a corporation
of New York

Application June 30, 1930, Serial No. 464,897

13 Claims. (Cl. 223—55)

My invention relates to collar pressing machines and, while adaptable for use in pressing the points of collars known as the stiff or starched variety, is particularly adapted and will be found particularly useful in pressing the points of the so called soft or semi-soft collars, especially those with long, narrow, sharp points, usually made by what is known as the hand method. In making such collars, three and sometimes four plies of cloth are cut somewhat larger than the finished collar is intended to be. These plies of cloth are then secured together by a row of stitching, usually about three-sixteenth inch from the edge, which extends along one side and across the two ends of the collar. The collar is then turned inside out by hand, leaving the three-sixteenth inch margin of cloth between the edge and the stitching on the inside of the finished collar. It will be readily apparent that this large volume of cloth, crowded and bunched on the inside of the point of a narrow, sharp-pointed collar will leave the point very thick and have a tendency to bulge the edges of the collar at each side of the point beyond the desired finish line. In laundering, these points are usually pressed with a flat iron and, due to the extreme thickness of the cloth, these bulges are greatly exaggerated when flattened in the ironing operation and give the point of the collar a very unsightly and irregular appearance.

The general objects of my invention, therefore, are to provide a method of procedure and a means whereby the difficulties above set forth and heretofore encountered in the manufacture of collars are eliminated. More particularly, my invention provides a method of procedure and a means whereby the points of collar tops are formed to the precise shape desired and without unsightly bulges or irregularities.

I accomplish my objects generally by first forcing the points into the desired shape and then holding them in that shape during the pressing operation. Or, in other words, the edges of the point are first laterally confined in predetermined angular relation and heat and pressure are then simultaneously applied to permanently and smoothly form the collar point to the desired configuration.

It is to be understood that my invention is in nowise limited to any particular apparatus for performing the process but I have illustrated in the accompanying drawings one embodiment of a machine which may be conveniently utilized therefor.

In the drawings—

Fig. 1 is a side sectional elevation view, of a

machine adapted to perform my process and is taken in about the plane 1—1 of Fig. 6;

Fig. 2 is a fragmentary section of Fig. 1 in the plane, 2—2;

Fig. 3 is a perspective view of a presser inverted position;

Fig. 4 is a sectional view of Fig. 1 in the broken plane 4—4;

Fig. 5 is a sectional view of Fig. 4 in a plane 5—5;

Fig. 6 is a section of Fig. 1 in the broken plane 6—6, and turned 90 degrees in a clockwise direction;

Fig. 7 is a perspective view of a detail;

Fig. 8 is an inverted perspective view of a detail;

Fig. 9 is a front elevation view of my machine;

Fig. 10 is a plan view of the point of a collar top before it is finished by pressing and shaping in my machine;

Fig. 11 is a plan view of a point of a collar top after being pressed and shaped in my machine;

Fig. 12 is a plan view of the presing bed showing adjustable jaw plates for confining the lateral edges of the collar point during pressing;

Fig. 13 is a fragmentary side view of my machine showing, in partial section, an adjustable pressing head, and is taken about the plane 13—13 of Fig. 14;

Fig. 14 is a fragmentary plan view, partially in section, in the plane 14—14 of Fig. 13; and

Fig. 15 is a section of Fig. 12 in the plane 15—15.

Referring to Figs. 1, 4, 6 and 9 of the drawings, my device comprises a table, 1, forming a support for the machine proper and to which the base, 2, is secured by any suitable means. The front part of the base forms a support for a pressing bed, 3, which is electrically heated by means of the resistance element, 4, supplied with current by the wires, 5 and 6. Upon the rear portion of the base is formed the lower part of an oil-tight casing, 7, within which is mounted some of the actuating mechanism of the device. The casing is provided with an oil level gauge, 86, and with a cover portion, 8, secured to the lower part, 7, by screws, 9, passing through the flanges, 10, a gasket, 11, being interposed between the flanges to secure an oil-tight joint. Mounted in bearings, 12 and 13, secured to the cover portion, 8, is the worm, 14, driven by the pulley, 15, over which runs the driving belt, 16. The worm, 14, meshes with the worm wheel, 17, rotatably mounted on shaft, 18, secured to the lower half, 7, of the casing. The worm wheel, 17, is secured to and drives the cam, 19, which actuates the pressing

15

head through the mechanism now to be described.

Mounted in the cover portion, 8, of the casing, and slightly above and parallel to worm shaft is a shaft, 20, upon which is mounted the crank, 21, provided with the angularly disposed arms, 22 and 23. The depending arm, 23, is provided at its lower extremity with a cam following roller, 24, (see Fig. 4) which coacts with the slot, 25, in cam, 19. There is also loosely mounted on the shaft, 20, the lever, 26, provided with the offset bearing collar, 27, (see Fig. 6) and having at its extremity a bifurcated portion, 28. Secured to the lever, 26, is a depending stud or cap screw, 29, which passes rather loosely through an opening, 30, in arm, 22. Compressed between arm, 22, and washer, 31, which is supported by the head of the stud, 29, is a rather stiff helical spring, 32.

From the foregoing it will be apparent that as the cam, 19, rotates it will move the depending arm, 23, toward position, 23', and depresses the arm, 22, to the position, 22'. Since the spring, 32, is rather stiff, the downward movement of the arm, 22, to the position, 22', will carry with it the lever, 26, but, in the event that the movement of the lever, 26, should be stopped before the arm, 23, reaches the position, 23', arm, 22, will move away from arm, 26, and compress the spring, 32.

Secured to the front part of the cover portion, 8, by means of screws, 33, is a vertically extending cylindrical or tubular element, 34, in which is slidably fitted a plunger, 35. The freedom of movement of the plunger in the cylinder may be controlled by the adjusting screws, 37, (see Figs. 6 and 9). The plunger, 35, is provided with an opening, 36, therein, into which the bifurcated end of lever, 26, projects and engages a roller, 37, secured to the plunger, 35, on the axis, 38. The bottom of the plunger, 35, is hollow and internally threaded to receive the stem, 39, of the pressing head, 40. Secured to the bottom of the pressing head, 40, by means of screws, 41, is a pressing element, 42. The stem, 39, is hollowed to receive the helical spring, 43, which is compressed between the inside top of the stem, 39, and the head, 44, of the finger, 45. It will be apparent that the stem, 39, may be threaded any desired distance into the plunger, 35, and secured in position by means of lock nut, 46.

Referring more particularly to Figs. 1, 4, 7, 8 and 9, there is secured to the pressing bed a fixed plate, 47, provided on the rear left portion thereof with an upright bearing, 48. Pivoted on the axis, 49, in the bearing, 48, is the crank, 50. The upper end of the crank, 50, is provided with a slotted opening, 51, which embraces a roller bearing, 52, (see Fig. 1) supported on the rear side of the pressing head, 40. It will be apparent that as the pressing head descends crank, 50, will be forced downwardly and the lower end, 53, thereof will move to the left as viewed in Fig. 9. The pressing bed, 3, is provided with an upstanding rib, 54, (see Fig. 1) which is received within a complementary slot, 55, (see Fig. 7) in the fixed plate, 47. Resting upon the pressing bed, 3, is a slideable plate, 56, provided with a slot, 57, which fits over the rib, 54, on the pressing bed and the said plate, 56, is slidably secured to the pressing bed by means of the element, 58, (see Figs. 4, 5 and 8). The plate, 56, is provided with a portion, 59, (see Figs. 4 and 7) which extends along the rear side of plate, 47. This portion of plate, 56, is provided with a recess or opening,

60, adapted to receive the lower end, 53, of the crank, 50. The end, 53, of the crank, 50, depends into the opening, 60, and engages a plunger, 61, which is mounted in an opening, 62, in plate, 56. The plunger, 61, is secured in position by means of the screw, 63, which also serves as an adjusting means for regulating the distance which the plunger, 61, projects from its cylinder. 5

As the crank, 50, is depressed by the downward movement of the pressing head the lower end, 53, of the crank will be forced against the end of the plunger, 61, and the spring, 64, behind the plunger, 61, is understood to be of sufficient stiffness so that a sliding movement of the plate, 56, toward the plate, 47, will be effected without compressing this spring, the purpose of the spring being to permit some additional movement of the crank, 50, after the plate, 56, has been moved to the left and its further movement in that direction is positively prevented by contact with the plunger as will be hereinafter described. 10 15 20

Referring particularly to Figs. 4 and 7, it will be apparent that the assembled plates, 47 and 56, form a notch, 65, having its sides disposed at an angle conforming to the angle, A, of the 25 collar point, as shown in Fig. 4, and that the sides of the notch are formed by jaw plates, 66 and 67, which may be removed and replaced by other jaw plates to provide a notch or opening angularly conforming to different collar points. It is 30 to be understood that the sides, 68 and 69, of the presser, 42, (see Fig. 3) are disposed at an angle conforming to the angle, A, of the collar point and that the presser in its downward movement just clears the edge of the jaw plate, 66. 35

Since the angle, A, is not uniform in every style of collar and since it is desirable that the angle between the jaw plates and the angle between the lateral faces of the presser shall conform to each other and to the angle at the point of the collar, 40 it is desirable that the angle between the jaw plates be adjustable, and that for any given angle between the jaw plates the presser be adjustable so that the lateral edge thereof in descending just clears the edge of the jaw, 66. Accordingly, I 45 have provided jaws and a presser which are adjustable, but before describing these modifications it is believed the invention will be better understood by first explaining the operation of the machine. 50

In operation, it is to be understood that the mechanism is being driven at appropriate speed by means of the belt, 16, and that the mechanism may be put in or out of operation by suitable 55 clutches actuated by the foot of the operator or otherwise. Assuming the parts to be in the positions shown by the solid lines in Fig. 1, the operator places the collar point on the pressing bed and between the jaw plates, 66 and 67, in the position shown in Fig. 4. That is, the edge of the 60 collar is pressed against the jaw plate, 66. To prevent injury to the operator a finger guard, 70, is shown in Figs. 4 and 9, which extends across the space between the jaw plates. As the cam, 19, rotates the depending portion, 23, of the crank, 21, is moved to the position, 23', and the arm, 22, is moved downwardly to the position, 22'. Inasmuch as the spring, 32, is quite stiff, this downward movement of the arm, 22, pushes the lever, 26, downwardly and the lever, 26, in turn, forces the plunger, 35, and the presser, 42, downwardly. As the presser descends the holding finger, 45, is brought into contact with the collar, 71 (see Fig. 1) and serves to hold the collar point in placed position during the further 75

descent of the presser head. As the presser descends, the crank, 50, is forced downwardly and the lower end thereof coacting with the plunger, 61, begins to move the plate, 56, to the left. The 5 downward movement of the presser, 42, and the movement of the plate, 56, are so timed that the jaw plate, 67, does not reach the edge of the collar until after the presser has descended below the top plane of the jaw, 67. It is to be understood, 10 however, that the jaw plate, 67, is brought into contact with the face, 69, (see Fig. 3) of the presser before the presser reaches the collar. During the downward movement of the presser, 42, finger, 45, remains in contact with the collar, 71, 15 and gradually recedes into the presser as the spring, 43, is compressed.

After the presser, 42, is brought into contact with the collar, any further downward movement thereof and of the actuating lever, 26, is prevented. At this point, the arm, 22, of the crank, 21, leaves the lever, 26, and compresses the spring, 32, during the further downward movement of the arm, 22. Thus, the device is adapted to press collars of various thicknesses without any adjustment whatever.

It will be apparent that the movement to the left of the plate, 56, is positively prevented as the jaw plate, 67, comes into contact with the lateral face, 69, of the presser. At this point 30 the plunger, 61, begins to recede against the compression of spring, 64, so that the jaw plate, 67, is held in yielding contact with the lateral face, 69, of the presser.

During the interval of time that the presser 35 is held in contact with the collar, and which is determined by the length of the straight part, 72, of the slot in cam, 19, heat is being applied to the collar and the point is being pressed in one direction by the presser head, 42, and the 40 edges of the point are being pressed in a direction at right angles thereto because of the jaws, 66 and 67, which prevent any lateral movement thereof.

Referring now more particularly to Figs. 12, 13, 45 14 and 15, I will describe the modification of my invention shown therein whereby the lateral pressing jaws and the presser are made adjustable to conform to different point angles. In the modified form, the plate, 47', which carries the 50 bearing, 48, is provided with slotted holes, 73 and 74, through which pass screws securing the plate to the pressing bed, 3. By means of these slotted holes the plate, 47', may be moved a limited distance to the right or the left and secured 55 in any position within the limits of its movement. Secured to the plate, 47', is a movable jaw plate, 66', having a corner, 75, thereof in contact with an edge of sliding plate, 56'. Plate, 66', is secured to the plate, 47', by means of a screw, 76, 60 which passes through an arcuate, slotted opening, 77, in the plate, 66'. This arcuate slot has its center at the point, 75, so that when the screw, 76, is loosened the plate, 66', may be moved angularly about the point, 75, as a center.

65 Likewise the jaw plate, 67', is secured to the sliding plate, 56', by means of screws, 78 and 79, passing through arcuate slots in the plate, 67', and which are described with the point, 80, as a center. By loosening the screws, 78 and 79, the 70 jaw plate, 67', may be moved about the point, 80, as a center and secured in various angular relations to the jaw plate, 66'. Thus the lateral forming, forcing or pressing jaws may be adjusted to conform to the angle of any collar point.

75 It is to be understood that pressers, such as 42,

having their lateral faces disposed at various angles are provided to conform to the various collar angles.

In view of the fact that the jaw plate, 66', is adjustable to various angles and it is always 5 desirable that one of the lateral faces of the presser in its downward movement just clears the edge of this jaw plate. It is necessary to provide some means for angularly adjusting the presser. In order that the extreme point of the collar 10 may be pressed, it is also quite essential that the point, 81, (see Figs. 3, 13 and 14) should be maintained substantially in vertical alignment with the point, 75, (see Fig. 12) on jaw plate, 66'. That is, it should remain substantially against the 15 edge, 82, on the sliding plate, 56'. It will be apparent from a consideration of Fig. 1 that the stem, 39, carrying the presser head, 40, to which the presser, 42, is attached, may be turned about its axis provided the nut, 46, is loosened and the 20 crank, 50, disengaged therefrom. To eliminate the necessity of disengaging crank, 50, I have provided the inner edge of the presser head, shown in Figs. 13 and 14, with a circumferential slot, 83, and have affixed a roller bearing, 84, to the 25 crank, 50. By this arrangement the presser head, 40, and the attached presser may be turned by loosening the nut, 46, so that the edge, 68, will lie in substantially the same vertical plane as the 30 side of the jaw plate, 66'. However, in so turning the presser, the point, 81, which was heretofore in vertical alignment with the edge, 82, of plate, 66', will be moved away from this edge and it is therefore necessary that the presser head shown in Figs. 13 and 14, be provided with slotted holes, 35 35 through which pass the screws, 41, secured to the presser. I have thus provided both a turning and a sliding adjustment for the presser so that it may be adjusted to conform to the angle 40 between jaw plates, 66' and 67', and to the angle of the collar.

Since the sliding plate, 56 or 56', moves towards jaw, 66 or 66', in forcing the lateral edges of the collar into the proper angular relation there is 45 sometimes a tendency to force the collar out of the jaws where the edge of the jaw plate, 66 or 66', is disposed at an angle which is too obtuse to the direction of movement of the plate, 56 or 56'. For example, there is more of a tendency to force the collar out of the space between the jaws 50 when the jaw plate, 66, is disposed at the angle shown in Fig. 7 than when it is disposed at the angle of the plate, 66', shown in Fig. 12. Therefore there is some advantage in arranging the 55 edge of the jaw plate, 66 or 66', at an angle of 90 degrees or less to the direction of movement of the plate, 66'.

From the foregoing it will be apparent that I have provided a machine for pressing and shaping the points of collars which will maintain the lateral edges of the points in precise, predetermined angular relation during the pressing operation, so that all lateral spread or bulging of the points is prevented. Because of the yielding pressing mechanism the device is adapted to 60 press collars of any thickness without the necessity of adjustment, and the lateral pressing jaws may be readily adjusted together with the presser to conform to any point angle.

While I have described my invention in its preferred embodiment it is to be understood that the drawings are merely illustrative, that the words which I have used are words of description rather than of limitation, and that changes within the purview of the appended claims may be 70 75

made without departing from the true scope and spirit of my invention.

What I claim is—

1. In a device for shaping the point of a collar, the combination with a pressing bed upon which the point is placed, of a presser adapted to be brought into contact with the point under substantial pressure, means for holding the point on the bed to prevent displacement as the presser approaches, and means comprising a lateral movable member for confining the collar point during the pressing operation.
2. In a device for shaping the point of a collar, the combination with a pressing bed upon which the point is placed, of means for holding the point in placed position, means for maintaining the edges of the point in fixed angular relation, means for applying heat and pressure to the point, and means comprising a lateral movable member for confining the collar point during the pressing operation.
3. In a device for pressing the point of a collar, the combination with a presser conforming generally to the angle of the collar point, of a pair of angularly disposed jaws for preventing lateral spread of the collar point during the pressing operation, means for adjusting the angular disposition of the jaws to conform to various collar point angles, and means for adjusting the presser to conform to the angular disposition of the jaws.
4. In a device for pressing the point of a collar, a pressing bed upon which the collar point is placed, a fixed jaw on said bed against which one edge of the collar point is placed, a presser, means for yieldingly bringing the presser into contact with the collar point, a second, movable jaw, and means for yieldingly bringing said movable jaw into contact with the side of the presser and the other edge of the collar point.
5. An apparatus as characterized for forming the corners of substantially flat garments, comprising a flat die movable in one direction to apply flatwise pressure to the garment, and an edge die movable in a direction substantially at right angles to the direction of movement of said flat die to apply edgewise pressure to the garment, and means for simultaneously moving said dies.
6. An apparatus as characterized for forming the corners of substantially flat garments, comprising a flat die movable in one direction to apply flatwise pressure to the garment, a fixed die against which an edge of the garment may be positioned, an edge die movable toward said fixed die and in a direction substantially at right angles to the direction of movement of said flat die to apply edgewise pressure to the garment, and means for simultaneously moving said flat die and edge die into operative engagement with the garment.
7. An apparatus as characterized for forming the corners of substantially flat garments, comprising a flat die movable in one direction to apply flatwise pressure to the garment, a fixed die against which an edge of the garment may be positioned, an edge die movable toward said fixed die and in a direction substantially at right angles to the direction of movement of said flat die to apply edgewise pressure to the garment, means for simultaneously moving said flat die and edge die into operative engagement with the garment.
8. In a device for pressing the point of a collar, a pressing bed upon which the collar is placed, a pair of jaws on said bed angularly disposed to conform to the angle of the collar point, a presser having a presser face conforming to the angle of the collar point, means for yieldingly bringing said jaws into contact with the edge of the collar point and means for bringing said presser into pressing engagement with the flat surface of the collar point.
9. In a device for pressing the point of a collar, a pressing bed upon which the collar is placed, a pair of jaws on said bed angularly disposed to conform with the angle of the collar point, a presser having a pressing face conforming to the angle of the collar point, means for yieldingly bringing said jaws into contact with the edges of the collar point, means for bringing said presser into pressing engagement with the flat surface of the collar point and means for simultaneously applying heat to said collar point.
10. In a device for shaping the point of a collar, the combination with the pressing bed upon which the point is placed, of a presser adapted to be brought into contact with the point under substantial pressure, means for holding the point on the bed to prevent displacement as the presser approaches, and means comprising relatively movable members for confining the collar point during the pressing operation.
11. In a device for shaping the point of a collar, the combination with a pressing bed upon which the point is placed, of a presser adapted to be brought into contact with the point under substantial pressure, means for holding the point on the bed to prevent displacement as the presser approaches, means comprising a fixed and a movable member for confining the collar point during the pressing operation and means comprising a yielding connection for forcing said movable member toward said fixed member.
12. An apparatus as characterized for forming the corners of substantially flat garments comprising a flat die movable in one direction to apply flatwise pressure to the garment, a fixed die against which an edge of the garment may be positioned, an edge die movable toward said fixed die to apply edgewise pressure to the garment and means for moving said flat die and the movable edge die into operative engagement with the garment.
13. An apparatus as characterized for forming the corners of substantially flat garments, comprising a flat die movable in one direction to apply flatwise pressure to the garment, a fixed die against which an edge of the garment may be positioned, an edge die movable toward said fixed die to apply edgewise pressure to the garment, means for moving said flat die and the movable edge die into operative engagement with the garment and means for heating the portion of the garment between said dies while said pressers are being applied.

GARRY J. DORMANDY.
